Primary Examiner — Sanjeev Paul(74) *Attorney, Agent, or Firm* — Cozen O'Connor(57) **CLAIM**

The ornamental design for a sleep pad, as shown and described.

DESCRIPTION

FIG. 1 is a front perspective view of a sleep pad showing our new design;

FIG. 2 is a top plan view of the sleep pad illustrated in FIG. 1;

FIG. 3 is a bottom plan view of the sleep pad illustrated in FIG. 1;

FIG. 4 is a left side elevation view of the sleep pad illustrated in FIG. 1;

FIG. 5 is a right side elevation view of the sleep pad illustrated in FIG. 1;

FIG. 6 is a front elevation view of the sleep pad illustrated in FIG. 1; and,

FIG. 7 is a rear elevation view of the sleep pad illustrated in FIG. 1.

The dashed broken lines in the figures represent portions of sleep pad that form no part of the claimed design. The dot-dash broken lines in FIGS. 1-7 define the bounds of the claimed design and form no part thereof.
